REFRIGERATOR CABINET

Robert R. Fink, Chicago, Ill., assignor to General Electric Company, a corporation of New York

Application October 23, 1957, Serial No. 48,215

Term of patent 7 years

(Cl. D67—3)

Fig. 1 is a front elevational view of a refrigerator cabinet embodying my new design;

Fig. 2 is a left side elevation thereof;

Fig. 3 is a fragmentary left side elevation thereof showing the door portion in section along lines 3—3 of Fig. 1; and

Fig. 4 is a fragmentary section, taken on line 4—4, looking in the direction of the arrows.

The right side, not shown, is substantially identical to the left side, shown.

I claim:

The ornamental design for a refrigerator cabinet, substantially as shown and described.
